UNITED STATES PATENT OFFICE.

WALTER H. PUMPHREY, OF NEW YORK, N. Y.

DESIGN FOR A SYRINGE-NOZZLE.

SPECIFICATION forming part of Design No. 33,246, dated September 25, 1900.

Application filed August 10, 1900. Serial No. 26,534. Term of patent 14 years.

To all whom it may concern:

Be it known that I, WALTER H. PUMPHREY, a citizen of the United States of America, and a resident of New York, county of New York, 5 State of New York, have invented and produced a new and original Design for a Syringe-Nozzle; and I do declare the following to be a full, clear, and exact description of the same, reference being had to the accompanying sheet of drawing, forming a part thereof.

My design is illustrated by a view in elevation.

As shown, the leading or material feature

of my design consists of a series of arms A A A, spirally disposed about a central tube B 15 and flared to form a bulb-like enlargement C.

Having described my invention, I claim—

The design for syringe-nozzle herein shown and described.

Signed at New York, N. Y., this 9th day of 20 August, 1900.

WALTER H. PUMPHREY.
